US00D904346S

(12) **United States Design Patent** (10) Patent No.: **US D904,346 S**
(45) Date of Patent: ** Dec. 8, 2020

(54) **SLEEVE FOR ELECTRONIC DEVICE**(71) Applicant: **CATALYST LIFESTYLE LIMITED**,
North Point (HK)(72) Inventors: **Joshua Wright**, Hong Kong (CN);
June Lai, Hong Kong (CN)(73) Assignee: **Catalyst Lifestyle Limited**, North Point
(HK)(**) Term: **15 Years**(21) Appl. No.: **29/665,172**(22) Filed: **Oct. 1, 2018**(30) **Foreign Application Priority Data**

Apr. 18, 2018 (CN) 2018 3 0159874

(51) LOC (12) Cl. **14-03**

(52) U.S. Cl.

CLAIM

The ornamental design for a sleeve for electronic device, as shown and described.

DESCRIPTION

FIG. 1 is a perspective view including a front, top and one side of the sleeve for electronic device;

FIG. 2 is a perspective view including a rear, bottom and opposite side of the sleeve for electronic device;

FIG. 3 is a planar view of the front of the sleeve for electronic device of FIG. 1;

FIG. 4 is a planar view of the rear of the sleeve for electronic device of FIG. 1;

FIG. 5 is a planar view of one side of the sleeve for electronic device of FIG. 1;

FIG. 6 is a planar view of an opposite side of the sleeve for electronic device of FIG. 1;

FIG. 7 is a planar view of the top of the sleeve for electronic device of FIG. 1; and,

FIG. 8 is a planar view of the bottom of the sleeve for electronic device of FIG. 1.
